(57) **CLAIM**

The ornamental design for a television receiver, as shown and described.

DESCRIPTION

1. Television receiver

1.1 : Front perspective view

1.2 : Rear perspective view

1.3 : Front

1.4 : Back

1.5 : Left

1.6 : Right

1.7 : Top

1.8 : Bottom

1.9 : Enlarged

The shading lines in reproductions 1.1 and 1.9 are used to show a portion of the display screen and of the transparent material that do not represent its surface ornamentation; the reproduction 1.9 is an enlarged view showing the portion of the upper middle part at the front side of the main body thereof; where the dot-dot-dash broken lines depict a crop line of the enlarged portion that forms no part of the claim; while the broken dashed lines depict portions of the television receiver that form no part of the claimed design.

1 Claim, 9 Drawing Sheets
